LITURGICAL FLOUNCING

Otto Frei, New York, N. Y.

Application December 7, 1950, Serial No. 13,315

Term of patent 7 years

(Cl. D92—1)

To all whom it may concern:

Be it known that I, Otto Frei, a citizen of the United States of America, residing in New York city, county and State of New York, have invented a new, original, and ornamental Design for a Liturgical Flouncing, of which the following is a specification, reference being had to the accompanying drawing, forming part thereof.

In the drawing:

The figure is a plan view of the liturgical flouncing embodying my new design.

The design unit which is shown between the dot and dash lines in the drawing is repeated in regular succession along the length of the flouncing.

I claim:

The ornamental design for a liturgical flouncing, substantially as shown and described.

OTTO FREI.
